UNITED STATES PATENT OFFICE.

HALFDAN A. STEEN, OF PITTSBURGH, PENNSYLVANIA, ASSIGNOR TO WESTINGHOUSE ELECTRIC AND MANUFACTURING COMPANY, A CORPORATION OF PENNSYLVANIA.

CONTROLLER FOR ELECTRIC MOTORS.

1,075,445.

Specification of Letters Patent. Patented Oct. 14, 1913.

Application filed January 3, 1910. Serial No. 538,160.

To all whom it may concern:

Be it known that I, HALFDAN A. STEEN, a subject of the King of Norway, and a resident of Pittsburgh, in the county of Allegheny and State of Pennsylvania, have invented a new and useful Improvement in Controllers for Electric Motors, of which the following is a specification.

My invention relates to controllers for electric motors and it has for its object to provide a motor-operated controller of the face plate type that shall be adapted for use as a master controller in governing the circuit connections for a plurality of independently operated control switches.

According to my present invention, I provide a face plate controller having a rotatable contact arm which is adapted to successively engage a plurality of stationary contact members for directly or indirectly governing an electric motor. The movable arm of the controller is connected to an electric driving motor through a train of gearing the members of which are so constructed and arranged that a continuous rotation of the motor produces a step-by-step motion of the movable arm. By this means, the movable arm is moved rapidly from one of its positions to the next, while, at the same time, a time element is introduced whereby the motor which is governed may be gradually accelerated.

Figure 1 of the accompanying drawings is a partially sectional elevation of a controller constructed in accordance with my invention and Fig. 2 is a view at right angles to that of Fig. 1 in which the controller face plate is disclosed. Fig. 3 is a fragmentary view, at right angles to that of Fig. 1, showing certain of the parts in a slightly different position in order to disclose them more fully, and Figs. 4 and 5 are detail views of the limit switch and the contact-finger of Fig. 2.

Referring to the drawings, the structure here shown comprises a vertical slab or plate 1 of insulating material which may constitute a panel of a switch board, a bracket 2 projecting outwardly therefrom, a rotatable shaft 3 on which a contact-bearing arm 4 is mounted, a plurality of cooperating stationary contact members 5 and 6 arranged in concentric circles on the plate 1, an electric driving motor 7 by which a rotatable movement of the contact arm 4 is produced, and an intermediate train of gear-

ing 8. The motor 7 is mounted at the outer end of the bracket 2 and the gearing 8 is disposed between the motor and the face plate 1 and comprises a stationary bearing frame 9 on which a shaft 10 is rotatably supported and from which a stud 11 projects, gear wheels 12 and 13, pinions 14 and 15 and a pawl 19. The pinion 14 is secured to one end of the motor shaft and meshes with the gear wheel 13 which is secured to the outer end of the shaft 10. A gear wheel 12 is driven by pinion 15 which is secured to one end of the shaft 10, a double reduction in speed being produced by the gearing between the motor shaft and the gear wheel 12.

A pawl holder 17 is secured to the outer end of the stud 11 by a screw 18 and projects downwardly therefrom, as shown in Fig. 1. A pawl 19 is pivotally secured to the lower end of the holder 17 and is provided with projections 20 which are forced into engagement with the teeth of a gear wheel 21 by means of a spring 22 which is secured to the pawl holder 17. The gear wheel 12 is provided with a projection 23 in the form of a tooth which forces the projections 20 away from the wheel 21 by engaging the beveled side of one of them and then engages one of the teeth of the said wheel and causes rotative movement of the wheel through a slight angle. Further movement of the wheel 12 carries its tooth 23 away from the projections 20 and the wheel 21, whereupon the pawl 19 is forced inward by the spring 22 to lock the wheel 21 until the wheel 12 has made a complete movement of rotation.

The gear wheel 21 is secured to and insulated from a flange 24 by means of screws 26 and an insulating disk 25. The flange 24 is integral with the hub 27 of the arm 4 which is secured to the rotatable shaft 3. The arm 4 extends outwardly from the hub 27 in opposite directions and is provided with a pair of contact fingers 28 at each end, which may be of any suitable structure, but I prefer to employ devices which are similar to those shown in detail in Fig. 5 of the drawings. One end of the arm 4 is provided with a projection 29 having a roller 30 which is adapted to engage arms 31 of a pair of limit switches 32 which are located at opposite ends of the normal movement paths of the controller and serve to interrupt the circuit of the motor 7 in

order to bring the controller to rest when the extreme positions are reached.

Each of the limit switches comprises a rotatable member 33 having a contact finger 34, a ratchet tooth or shoulder 35 and a spring 36. The arm 31 projects from a collar 37 having a cam projection 38 and is connected to a holding pawl 39 by means of a spring 40. The contact finger 34 is movable into and out of engagement with a stationary contact terminal 41 by the above specified means, the operation of which will now be described. When the arm 31 is freed from engagement by the roller 30, the pawl 39 engages the shoulder 35 and the finger 34 is in contact with the terminal 41. Movement of the arm 31 by means of the projection 29 and its roller 30 exerts tension upon the spring 40 and bends the spring 36 until the cam projection 38 forces the pawl out of engagement with the shoulder 35 when the spring 36 will effect a quick movement of the finger 34 away from the contact terminal 41. As soon as the arm 31 is released the spring 40 will cause the parts to assume their normal positions. It will be understood that limit switches having different structural characteristics may be employed, if desired.

When it is desired to adjust the movable contact-bearing arm 4, the motor is operated in the opposite direction and, as already pointed out, it drives the gear wheel 12 at relatively low speed through pinion 14, gear wheel 13, jack shaft 10 and pinion 15. The continued rotation of the gear wheel 12 brings the projection 23 into engagement with the teeth of the gear wheel 21 once in every revolution of the wheel 12, the projection being adapted to temporarily release the pawl which locks the gear wheel 21. The arrangement of parts is such that the pawl projections 20 mesh with the gear teeth of the wheel 21 in succession. In this way, step by step, rotation of the gear-wheel 21 is produced and, since the gear teeth of this wheel are arranged to correspond in number and position to the control positions of the arm 4, the arm is moved from position to position without possibility of resting between regular control positions.

The operation of the motor may be governed by push button switches or by some other simple controlling means so that the device is well adapted for governing electrically operated printing presses and similar mechanisms in which it is desirable to

control the driving motor from various points or stations.

I do not wish to be limited to the specific structure illustrated in the drawings since it is evident that structural modifications may be effected within the spirit and scope of my invention.

I claim as my invention:

1. In a controller for electric motors, the combination with co-operating stationary and movable contact members, of an electric driving motor for the movable contact member, and an interposed driving connection comprising a gear wheel operatively connected to the movable member, a tooth-engaging means for locking the gear wheel against movement, and a single means operated by the electric motor to successively displace the tooth-engaging means and turn the gear wheel through a small angle.

2. In a controller for electric motors, the combination with a slab or face plate of insulating material, a set of stationary contact members thereon and a co-operating movable contact member, of an electric driving motor for the movable member, and an interposed driving connection comprising a gear wheel operatively connected to the contact member, means for locking the gear wheel, a continuously operating motor and a single means operated by said motor to intermittently release the gear wheel and move it through a slight angle at each rotation of the driving motor.

3. In a controller for electric motors, the combination with a slab or face plate of insulating material, a set of stationary contact members thereon and a co-operating movable contact member, of an electric driving motor for the movable member, of an interposed driving connection comprising a gear wheel secured to and insulated from the movable contact member, a pawl for normally preventing rotation of the gear wheel, a rotatable member having a projection for withdrawing the pawl and moving the gear wheel through a slight angle at each rotation of said member, and reducing gearing between the motor and the rotatable member.

In testimony whereof, I have hereunto subscribed my name this 23rd day of Dec., 1909.

HALFDAN A. STEEN.
